Specification for Design.

Patented Aug. 26, 1919.

Application filed March 21, 1919. Serial No. 284,219. Term of patent 3½ years.

To all whom it may concern:

Be it known that we, ISAAC N. WEBER and JESSE KASKEL, citizens of the United States, residing at New York, in the county of New York and State of New York, have invented a new, original, and ornamental Design for Dolls, Statuettes, Sculpture, and other Articles of Similar Nature, of which the following is a specification, reference being had to the accompanying drawing, forming part thereof.

The drawing shows a face view of the "Maggie" doll showing my new design.

We claim:

The ornamental design for a doll, statuette, sculpture or other article of similar nature, as shown.

ISAAC N. WEBER.
JESSE KASKELL.
